(57) **CLAIM**

The ornamental design for the tube lamp as shown and described.

DESCRIPTION

FIG. 1 is a front and top perspective view of the tube lamp, showing my design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled “9” in FIG. 1;

FIG. 10 is an enlarged view of an encircled area labeled “10” in FIG. 2; and,

FIG. 11 is an enlarged view of an encircled area labeled “11” in FIG. 2.

The broken lines depict portions of the tube lamp that form no part of the claimed design.

The dot-dash broken lines shown in FIGS. 1, 2, 9, 10, and 11 framing portions of the tube lamp for enlargements purposes form no part of the claimed design.

1 Claim, 11 Drawing Sheets
